UNITED STATES PATENT OFFICE.

ERNEST B. FAHNESTOCK, OF PLANDOME, NEW YORK; EDITH MARY JORDAN AND FRANCES HODGSON BURNETT, BOTH OF PLANDOME, NEW YORK, EXECUTORS OF SAID ERNEST B. FAHNESTOCK, DECEASED.

CONDUIT FOR VOLATILIZED FLUIDS.

Application filed April 15, 1918. Serial No. 228,543.

To all whom it may concern:

Be it known that I, ERNEST B. FAHNESTOCK, a citizen of the United States of America, and a resident of Plandome, county of Nassau, and State of New York, have invented certain new and useful Improvements in Conduits for Volatilized Fluids, of which the following is a specification, reference being had to the accompanying drawings, forming a part thereof.

My invention relates to new and useful improvements in conduits for gaseous fuels, and its object is to provide a passage for volatilized fluids which will prevent the condensation thereof.

More specifically, its object is to provide a conduit for the volatilized fuel for internal combustion engines which may be interposed between the fuel supply jet and the engine cylinder in the form of a pipe or chamber and which is constructed of porous material so arranged that a limited amount of air may pass through its walls.

In order that my invention may be thoroughly understood, I will now proceed to describe the same in the following specification, and will then point out the novel features thereof in appended claims.

Referring to the drawings:

Figure 1 is an elevation partly in section, of an engine and a carburetor of ordinary construction with a conduit which embodies this invention interposed between them.

Figure 2 is a plan view partly in section of an engine manifold which also embodies this invention.

Figure 3 is a sectional end elevation of the conduit shown in Figure 1, the section being taken on the line 3—3 of the latter figure.

Figure 4 is a sectional end elevation of a conduit of modified construction which also embodies my invention.

Figure 5 is an elevation partly in section, of another arrangement of parts by means of which this invention may be used.

Like characters of reference designate corresponding parts in all the figures.

10 designates an internal combustion engine, 11 its intake and 12 a carburetor of standard construction. The carburetor is connected by a pipe fitting 13 with one end

of a cylindrical member of insulating material 14, the other end of which is connected by a pipe fitting 15 with the manifold 11. 55

16 is an air supply pipe leading from a jacket on the exhaust pipe of the engine (not shown), to a check valve 17 provided with an adjusting spring 18 and connected to an intake port 19 at any suitable point on 60 the member 14.

Within the member 14 is a tube 20 of porous material, in this case of felt, which is separated from the inner surface of the member by a spiral of resistance wire 21, 65 wound helically around the tube and connected at its ends with binding posts 22—23 by means of which it may be connected with a source of electrical supply.

Before more specifically describing the 70 structures shown in Figures 2, 4 and 5, I will point out the operation of this device. A volatile fluid is vaporized in the carburetor in the usual way and led into one end of the tube 20 through which it passes 75 to the engine manifold. In such conduits as have been used heretofore, there is a considerable condensation between the carburetor and the engine and various expedients have been resorted to to overcome this 80 difficulty. The passages are usually made of small diameter in order to maintain a high velocity of the gases even at low engine speeds, which detracts from the efficiency of high speeds. In this case this is not necessary. Whatever fuel has a tendency to condense, settles on the porous tube and air coming through the port 19 goes through the wall of the tube and revolatilizes such 85 condensed fluid. If heated air is led through 90 the pipe 16, its heat increases its volatilizing effect.

When it is desired to supply water vapor to the engine, steam either with or without air may be introduced by a pipe through 95 the port 19.

If a further heating effect is desired, an electric current may be passed through the resistance wire 21. This is particularly desirable in starting, especially with a fuel 100 which does not readily volatilize at atmospheric temperatures, such as kerosene. The amount of air which is permitted to pass through the wall of the tube 20 may be

regulated by adjusting the spring 18 of the check valve.

In Figure 2 the engine manifold is shown as constructed of two parts 30 and 31, which are adapted to be affixed to an engine, and a third member 32 within which and spaced from the inner surface thereof by a wire coil 33 is a porous tube 34. The volatilized fuel is admitted to the inside of the tube 34 through a port 35 and air is admitted to the inside of the member 32 and outside the tube 34 through suitable ports (not shown), similar to port 19 of Figure 1 which may be valve controlled if desired.

15 The operation of this structure is like that already described.

It is not necessary that the porous tube be made of felt as any other suitable material may be used. For example, in Figure 4, a 20 section of a tube is shown made of spirally wound metallic screen 38.

Figure 5 shows a simple arrangement of parts in which 50 designates a porous tube connected at 51 with an engine 52. At its 25 other end is a spray nozzle 53 controlled by a valve 55 for admitting a volatile liquid fuel. The length and thickness of the tube and its porosity are in this case so proportioned that enough air will pass through the 30 wall of the tube to make the desired explosive mixture at the engine intake. There is in this arrangement no carburetor other than that formed by the tube.

From the foregoing description it may be 35 seen that when a carburetor is used to admit volatile fuel and air to the porous conduit, the carburetor needs no mixing chamber beyond its fuel jet. It is also clear that it is not necessary to restrict the area of the 40 conduit for the purpose of insuring high velocity or to restrict the length of the conduit for the purposes of minimizing condensation. Thus, by the use of this invention one of the serious difficulties in the 45 construction and operation of internal combustion engines, is entirely avoided.

Structures of preferred form and construction have been illustrated and described for the purpose of showing ways in which 50 this invention may be used, but the inventive thought upon which this application is based, is broader than these illustrative embodiments thereof, and I therefore intend no limitations other than those imposed by 55 the appended claims.

What I claim is:

1. The combination with an internal combustion engine provided with an intake port, 60 of an intake conduit having the passage therethrough in communication with a source of fuel supply and connected with the intake port, said intake conduit having a wall of capillary porosity in communication at the outside with a source of air and whereby air drawn through the porous wall of the 65 conduit into the passage therein will take up fuel condensing within the passage in the conduit and a casing surrounding the conduit and providing an air chamber there-

the conduit into the passage therein will take up fuel condensing within the passage in the conduit.

2. The combination with an internal combustion engine provided with an intake port, 70 of an intake conduit having the passage therethrough in communication with a source of fuel supply and connected with the intake port, said intake conduit having a wall of capillary porosity in communication at the outside with a source of air whereby air drawn through the porous wall of the conduit into the passage therein will take up fuel condensing within the passage in the conduit and means for heating the air thus drawn through the wall of the conduit into the passage aforesaid.

3. The combination with an internal combustion engine provided with an intake port, 75 of an intake conduit having the passage therethrough in communication with a source of fuel supply and connected with the intake port, said intake conduit having a wall of capillary porosity in communication at the outside with a source of air and whereby air drawn through the porous wall of the conduit into the passage therein will take up fuel condensing within the passage in the conduit and a casing surrounding the conduit and providing an air chamber thereabout.

4. The combination with an internal combustion engine provided with an intake port, 80 of an intake conduit having the passage therethrough in communication with a source of fuel supply and connected with the intake port, said intake conduit having a wall of capillary porosity in communication at the outside with a source of air and whereby air drawn through the porous wall of the 85 conduit into the passage therein will take up fuel condensing within the passage in the conduit and a casing surrounding the conduit and providing an air chamber thereabout, said casing having an air intake 90 provided with a check valve.

5. The combination with an internal combustion engine provided with an intake port, 95 of an intake conduit having the passage therethrough in communication with a source of fuel supply and connected with the intake port, said intake conduit having a wall of capillary porosity in communication at the outside with a source of air whereby air drawn through the porous wall of the 100 conduit into the passage therein will take up fuel condensing within the passage in the conduit and a casing surrounding the conduit and providing an air chamber thereabout, said casing having an air intake and 105 means for heating the air passing to said intake.

6. In combination with an internal combustion engine, a fuel supply therefor, an interposed hollow conduit having a wall of 110

capillary porosity, a member surrounding the conduit, spaced therefrom, and adjustable means for admitting air to the space between the member and the conduit.

5 7. In combination with an internal combustion engine, a fuel supply therefor, an interposed hollow conduit having a wall of capillary porosity, a member surrounding the conduit, means for admitting air to the 10 inside of said member, and means for heating the air.

8. In combination with an internal combustion engine, a fuel supply therefor, an interposed hollow conduit for conducting fuel 15 from the fuel supply to the engine having a wall of capillary porosity, a member surrounding the conduit, a resistance wire surrounding the conduit and arranged to provide an air space between the member and 20 the conduit, and means for admitting air to the said air space.

9. In combination with an internal combustion engine, a fuel supply therefor, an interposed hollow conduit for conducting 25 fuel from the fuel supply to the engine having a wall of capillary porosity, a member surrounding the conduit, a resistance wire surrounding the conduit and arranged to provide an air space between the member 30 and the conduit, and a check valve arranged to admit air to said air space.

10. In combination with an internal combustion engine, a fuel supply therefor, an interposed hollow conduit for conducting 35 fuel from the fuel supply to the engine having a wall of capillary porosity, a member surrounding the conduit, a resistance wire surrounding the conduit and arranged to provide an air space between the member 40 and the conduit, a check valve arranged to admit air to said air space, and means for adjusting said check valve.

11. In combination with an internal combustion engine, a fuel supply therefor, an interposed hollow conduit having a wall of 45 capillary porosity, a member surrounding the conduit, and a pipe arranged to lead hot air from the engine to the inside of the member.

12. In combination with an internal combustion engine, a fuel supply therefor, an interposed hollow conduit having a wall of capillary porosity, a member surrounding the conduit, means for spacing the conduit from said member, a pipe arranged to lead 55 hot air from the engine to the space between the member and the conduit, and means for regulating the quantity of air passing into said space.

13. A conduit comprising a hollow member, means for admitting a volatilized fluid to said member, at one part thereof and for discharging said volatilized fluid from another part thereof, said member having a 60 wall of capillary porosity between said admission and discharge parts thereof arranged to receive condensed particles of the fluid, and means for passing air through said porous wall to revolatilize said condensed particles of the fluid. 65

14. A hollow member, means for admitting a liquid fuel in a finely divided state at one part thereof and for discharging said fuel together with air at another part thereof, said member having a wall of capillary 70 porosity between said admission and discharge parts, and means for passing air through said porous wall whereby said liquid fuel is prevented from settling on said porous wall. 75

In witness whereof, I have hereunto set my hand this 11 day of April, 1918.

ERNEST B. FAHNESTOCK.
